UNITED STATES PATENT OFFICE.

PHILIP D. JOHNSTON, OF COLD SPRING, NEW YORK.

INTERNAL-COMBUSTION ENGINE.

1,344,407.

Specification of Letters Patent. Patented June 22, 1920.

Application filed November 24, 1911. Serial No. 662,111.

To all whom it may concern:

Be it known that I, PHILIP D. JOHNSTON, a citizen of the United States, and residing at Cold Spring, Putnam county, State of New York, have invented a certain new and useful Internal-Combustion Engine, of which the following is a specification.

The objects I have in view are—

1st. To produce an internal combustion engine capable of successful use with heavy liquid hydrocarbon fuels of the type which ordinarily and heretofore have had a tendency to break up into their constituent elements when used in an engine, and because of incomplete combustion precipitate tar or other deposits in the combustion chamber and on the internal surfaces of the cylinder.

2nd. To make it possible to profitably use such heavy liquid hydrocarbon fuel which the ordinary engine is incapable of, by causing complete combustion and consequent freedom from deposits.

3rd. To govern under varying loads, particularly overcoming the usual difficulty incident to variable stroke fuel feed pumps and consequent uncertain ignition while under low loads.

4th. To simplify the fuel feed connections on an engine with a plurality of cylinders, using but a single pump for a multiplicity of cylinders.

5th. To make the mechanism simple, very accessible, and capable of utilization on engines of the two-stroke, four-stroke or other type, with vertical, inclined or horizontal cylinders, having either a single or a plurality of cylinders.

These and further objects will more fully appear from the following specification and accompanying drawings, considered together or separately.

In the drawings, Figure 1 shows a side elevation of an embodiment of the invention, in a two-cycle, two-cylinder vertical engine.

Fig. 2 is a vertical part section of the same, showing some parts which are omitted in Fig. 1.

Fig. 3 is an enlarged view, partly in section, of the fuel atomizer and injector.

Fig. 4 is a transverse section of the same, taken on the line 4—4 of Fig. 3.

Fig. 5 is a similar view, taken on the line 5—5 of Fig. 3.

Fig. 6 is a front view, showing a portion

of the controlling mechanism for the fuel feed, together with the governing mechanism.

Fig. 7 is a side view of the same, some parts being in section.

Fig. 8 is a transverse section of the same, taken on the line 8—8 of Fig. 7.

Fig. 9 is an enlarged view, in section, of the valve seat of the fuel atomizer and injector.

Fig. 10 is an enlarged view of the valve; and

Fig. 11 is a section on the line 11—11 of Fig. 3.

In all of the views, like parts are designated by the same reference characters.

I will describe my invention in connection with the two cylinder, two-cycle vertical engine illustrated. I will predicate this description by the statement that most of the features of the invention may be used on an engine of a different type, style and arrangement.

The engine embodies the usual shaft 1, crank case 2, which is not used in this example, as a primary compression chamber, and cylinders 3, 3^a. Each cylinder as shown in Fig. 2 is closed by the usual water-jacketed cylinder head 4, and has a lower cover or head 5. The piston 6, which is of the usual barrel type, is connected to the piston rod 7, which passes through the usual stuffing-box in the bottom cover 5, this stuffing box being to pack against low pressure air only. The piston rod is connected by the cross-head 8 and connecting rod 9 to the crank 10. This general form of two-cycle engine is well known, the combustion chamber 11 being above the piston 6 and the primary compression chamber 12 being below it. Air at atmospheric pressure is drawn through the manifold 13 to ports or passages 14 into the primary compression chamber 12; the port 14 being exposed or unmasked by the bottom of the piston. The air, after being compressed by the downward movement of the piston, is admitted to the combustion chamber through the transfer passage 15, there being a port 16 below and a somewhat shallower port 17 above. A port 18 in the piston is adapted to register with the port 16 when the piston is at the bottom of its stroke; at the same time the port 17 will be above the top of the piston. The

usual deflecting shield 19 carried by or

made integral with the piston, is employed adjacent to the port 17. The exhaust port 20 connects with a manifold 21, the various cylinders of the engine having their exhaust ports connected to this manifold. By making the port 17 with its upper edge somewhat lower than the upper edge of the port 20, the exhaust port will be opened before the transfer port is and the pressure within the combustion chamber at the end of the stroke will be reduced before the scavenging begins. Also by making the port 17 lower and shallower, as shown, the ports 18 and 16 will come in juxtaposition before the top of the piston exposes or unmasks the port 17. Hence the transfer passage 15 will be in communication with the primary compression chamber before such passage is in communication with the combustion chamber and the compressed air from the compression chamber will enter this transfer passage first, before the upper end of the passage is opened, hence wire drawing will be prevented and the compressed air will fill the passage 15 under the pressure of the primary compression chamber, before the transfer passage is opened into communication with the combustion chamber. This insures prompt action of the scavenging air and thorough expulsion of the spent gases.

The combined atomizers and injectors 22, 22^a are shown on top of the cylinders, there being one for each cylinder. The atomizer and injector includes the vaporizer 23, which in the embodiment of the invention chosen for illustration is in the form of a hot ball or sphere. The vaporizer is unjacketed and communicates with the combustion chamber by means of a pipe or tube 24. Fuel is injected into the hot ball, ignition begins and inflammation is transferred from the vaporizer at the same time the fuel passes into the combustion chamber from the vaporizer. Before referring to the details of the injector, reference being had to Fig. 2, an air compressor 25 is shown. This air compressor may be operated in the usual manner, and forces air at a preferably certain definite pressure into a storage tank 26. The stored compressed air is used in starting the engine as well as in operating the atomizers. The storage tank is common to the several cylinder of the engine. This storage tank is connected by a pipe 27, to a hollow coil 28 (see Fig. 1) located in the exhaust manifold 21; so as to be subjected to the hot exhaust products of combustion from the cylinders, the pipe 27 being divided into two branches 29, 29^a to communicate with the two injectors 22 and 22^a. Referring again to Fig. 2, a fuel pump 30 is driven at constant speed and constant stroke from a lay shaft 31, this lay shaft being driven by any suitable connections from the shaft 1, and preferably at the same speed as the shaft 1. The pump 30 is provided with a loaded valve 30^a, so that it will pump oil only at the certain definite pressure for which the valve is set. The pump is shown as supported upon the auxiliary supply tank 32, to which the fuel is supplied in the ordinary manner, in proper quantities. The fuel pump 30 connects with the pipe 33, which is provided with a hollow coil 34 in the exhaust manifold 21 and has branches 35, 35^a to the two injectors 22, 22^a. The pump 30 also connects with a pressure reservoir 36 which is connected by a pipe 37 to the air supply tank 26. This pressure reservoir may be placed, as shown, or at any convenient place on the engine. The purpose of this arrangement of pipes and pressure reservoir 36, together with the pump having the loaded valve, is to avoid the necessity of a variable stroke of the pump in order to accommodate different loads on the engine. The intention is to have the pressure of the oil in the pipe 33 the same as that of the air in the pipe 27. This is accomplished by means of the pipe 37 and tank 36. The pipe 37 is shown as having a cock 38, which can shut off the supply of air through the pipe 37 when the engine is stopped to keep the air from forcing the fuel up through the pipe 33 to the atomizers. Should the loaded valve on the pump be improperly adjusted, it is convenient to have some means of observing the level of the fuel in the tank 36 so that this tank will not become empty nor yet overflow through the pipe 37 into the air supply tank 26. The air supply tank 26 may also be provided with an escape valve, or the air compressor 25 may be provided with a loaded valve so that the air pressure in the system will not exceed a certain maximum amount. Both the air and fuel before they reach the igniter pass through the coils in the exhaust manifold and are raised to a relatively high temperature. The branches 29, 29^a and 35, 35^a are made as short as possible, and may be jacketed so that heat of the fuel and air will be retained, to the end that the air and fuel will remain in them a minimum length of time and will not have an opportunity to become chilled or reduced in temperature to any extent before entering the atomizer and injector. The atomizer and injector is shown best in Figs. 3, 4, 5, 9, 10 and 11. It embodies a casing 39, which carries a valve 40 and a valve seat 41. The valve 40 is mounted in the casing so that it may reciprocate and at the same time be free to revolve. To accomplish this, it is provided with a winged guide 42 near its forward end, and a guiding piston 43 at its rear end. The valve is normally pushed against its seat by a spring 44, and is retracted from its seat by means of an arm 45 carried upon a shaft 46. This shaft ex-

tends through a stuffing-box in the casing, as shown in Fig. 5, and is provided with an arm 47, by means of which it is rotated. The valve 40 is best made in two parts, 5 as shown in Fig. 3, the head being removable from the stem, so that a single sized stem may be used in a different sized engine with the valve head suitable to the size of engine. The valve seat is best shown in 10 Fig. 9; it is conical, and adapted to make a close fit with the valve 40. One or more ports 48 communicate with this seat, the ends of the ports in communication with the seat being reduced in size so as to make a 15 small opening. These ports 48 are connected to passages 49, the ends being inclosed by screw plugs 50. The supply pipe 35 or 35^a is connected to either end of the passage 49, as desired. By having two of the ports 48, 20 greater flexibility in construction can be obtained, and it is possible to use a single sized injector for a large number of different sizes of engines. As shown in the drawings, one of the ports 48 is in communication with the 25 fuel supply by means of the passage 49, the branch 35 and pipe 33. The passages 49 are provided with openings covered with screw plugs 51, adjacent to the ports 48, so that a wire or tool can be introduced when 30 necessary, in case the passage becomes choked by foreign matter carried in the liquid fuel.

The arm 47 is adapted to be moved at intervals during the operation of the engine, 35 so as to retract the valve 40 from its seat and allow the air, which enters the interior of the casing 39 through the opening 52 under pressure, to blow or force the liquid fuel through the injector, thus completely atomizing the fuel and intimately mixing it with 40 the heated air. The fuel and air both being heated and both under high pressure, will be released upon the withdrawal of the valve 40 from its seat, and both will be violently driven against the seat and into the 45 vaporizer 23. The liquid fuel will be immediately flashed into vapor, owing to its high temperature, and will be broken up, by the action of the air, which action is increased 50 by the fact that the ports 48 are inclined so as to direct the liquid fuel against the air current, as shown in Fig. 9. The liquid fuel is also broken up and commingled with the air by means of scorings 53 formed in the 55 valve seat. The liquid fuel is forced through and is subjected to high temperature in the coil 34 and will be maintained under the pressure of the air stored in the tank 26, and the small quantity necessary for the operation of a particular cycle of the engine 60 will be released through the retraction of the valve 40. This fuel will immediately flash into gas, and will be blown into the hot ball 23. It will be blown by the accumula-

tion of air under the same pressure, which 65 blast will prevent the deposit of any tarry mixture or other residuum on the valve-seat or any parts of the igniter.

The operation of the arm 47 is preferably by means of the mechanism shown in Figs. 70 6 and 7. The lay shaft 31 carries a cam 54. This cam engages with a block or wiper 55, sliding in a frame 56. The lower end of the block is held against the cam 54 by means of a spring 57. In the same frame 56 with 75 the block 55 is a second block 58. The block 58 is connected to the arm 47 by means of a rod 59. This block 58 lies alongside of the block 55 and moves with it. The connection between the blocks 55 and 58 is by means 80 of a latch 60. This latch is pivoted to the block 58, and its hooked upper end engages with the top of the block 55. The lower end of the latch 60 is formed with a projection 61. The path of movement of the 85 projection 61 is intercepted by the location of a block 62, movable upon the frame 56. This block has an inclined groove 63 (see Fig. 6) engaged by a bolt 64. By moving the block 62 horizontally, it will be moved 90 in a vertical direction by the engagement of the bolt 64 with the inclined groove 63. The block 62 is moved in accordance with the speed of the engine by means of a governor 95 65. As the speed changes, this block 62 is elevated or depressed, owing to the movement of the block on its supporting bolt 64. The engagement of the projection 61 on the latch 60 with the block 58 will vary according to the position of the block. It is apparent that upon the block 55 being elevated by engagement with the cam 54, the block 58 will be elevated with it, owing to the engagement of the latch 60 with the block 55. The elevation of the block 58 100 105 will, through the agency of the rod 59, swing the arm 47 and open the injector valve. The valve will remain open and the extent of opening will increase until the projection 61 engages with the governing 110 block 62, whereupon the latch 60 will be turned upon its pivot against the tension of the spring 66, releasing the latch 60 from the block 55 and allowing the block 58 to descend. It will descend by means of its 115 own weight, and also by the action of the spring 44 closing the valve 40 upon its seat 41. The extent of opening will control the amount of fuel; the farther the valve is removed from its seat, the greater will be the 120 extent of opening, and consequently the amount of fuel to be atomized. This extent of opening will be in relation to the duration of opening. I make no claim in this application to the specific form of governing mechanism employed, but I regard it as essential to the best accomplishment of my 125 invention to utilize a device which will open

the injector valve always at a predetermined point, and close it at variable intervals, depending upon the load.

The operation of the entire device is as follows: Assuming that the piston compresses the charge of air in the combustion chamber to 300 pounds per square inch, the pressure in the tank 26 should be 350 pounds or more per square inch. The liquid hydrocarbon fuel in the branch 29 and the air in the branch 35 will be at the same pressure and at a temperature slightly lower than the temperature of the escaping gases. The cam 51 is so arranged that the injector valve 40 will always be opened just as the piston reaches the upper range of its movement. The hydrocarbon fuel which is blown by the air into the vaporizer as described, will become ignited and the products of combustion, together with the uncombusted fuel, will pass into the combustion chamber 11, wherein the combustion will be completed. I prefer to so proportion the parts that there will be an excess of air in the combustion chamber in order that all of the hydrocarbon injected will be consumed partly in the vaporizer and partly in the combustion chamber, as will be understood. The device is described in connection with a mechanism which will always open the injector valve at the same point of the cycle of the engine, the closing being determined by the governor at a variable time, depending upon the load on the engine. The fuel is always injected, therefore, when it is injected at all, at a definite point but the period of cut-off varies. The parts will be so proportioned that when running under no load the lateh 60 will not engage the block 55 and there will be no movement of the block 58.

The engine is started in the usual manner, such as by heating the vaporizer 23 by a torch and employing the ordinary well-known means for cranking the engine by air under pressure. After the engine is running, the vaporizer will be heated by the combustion of the fuel therein, the torch being used only for starting.

A very great advantage of my invention is that the fuel is used only in accordance with the load, and hence the engine is very economical, and the speed regulation very close. Another advantage is that a minimum quantity of fuel is stored adjacent to the injector, only enough to fill the branches 35 and passages 48. These passages are of a small size, hence the amount of fuel which is subjected to the heat will be very small, and quickly heated, and consequently in condition to flash into gas immediately upon release by the atomizer. By reason of the heating of fuel and air before admitting them to the injector or vaporizer, the cooling effect on the vaporizer or hot ball is reduced, especially when

running under low loads. The particular governing mechanism and the arrangement of the ports for scavenging disclosed herein, are not claimed in this application, but will form the subject-matter of an application or applications for patent to be filed subsequently.

In accordance with the provisions of the patent statutes, I have described the principle of my invention, together with the apparatus which I now consider to represent the best embodiment thereof; but I desire to have it understood that the apparatus shown is merely illustrative and that the invention can be carried out in other ways.

Having now described my invention, what I claim as new and desire to secure by Letters Patent, is:—

1. An internal combustion engine having an atomizing injector, said atomizing injector having a passage for air, means for impressing air under pressure in the passage, a tapered valve seat in the passage, a passage for liquid fuel entering through the valve seat, the outlet thereof being in the valve seat, means for impressing liquid fuel under pressure in the fuel passage, a tapered valve having a single head, means for engaging the head with the seat and closing the air passage and the fuel passage, said valve opening in the direction against the air pressure, and means for operating the valve in sequence with the operating cycle of the engine.

2. An internal combustion engine having an atomizing injector, said atomizing injector having a passage for air; means for impressing air under pressure in the passage; a tapered valve seat in the passage; a passage for liquid fuel extending through the valve seat, the outlet thereof being in the valve seat, said fuel passage being inclined in the direction opposed to the flow of the air; means for impressing liquid fuel under pressure in the fuel passage; a tapered valve, lying in the valve seat, and closing the air passage and also the fuel passage, said valve opening in the direction against the air pressure; and means for operating the valve in sequence with the operating cycle of the engine.

3. An internal combustion engine having an atomizing injector, said atomizing injector having a passage for air; means for impressing air under pressure in the passage; a tapered valve seat in the passage; a passage for liquid fuel, the outlet thereof being in the valve seat; a circumferential score or scores formed in the seat, between the fuel outlet and the outlet of the mixture; means for impressing liquid fuel under pressure in the fuel passage; a tapered valve, lying in the valve seat, and closing the air passage and also the fuel

passage, said valve opening in the direction against the air pressure; and means for operating the valve in sequence with the operating cycle of the engine.

5. An internal combustion engine having an atomizing injector, said atomizing injector having a passage for air; means for impressing air under pressure in the passage; a tapered valve seat in the passage; 10 a passage for liquid fuel, the outlet thereof being in the valve seat, said fuel passage being inclined in the direction opposed to the flow of the air; a circumferential score or scores formed in the seat, between the 15 fuel outlet and the outlet of the mixture; means for impressing liquid fuel under pressure in the fuel passage; a tapered valve, lying in the valve seat, and closing the air passage and also the fuel passage, said valve 20 opening in the direction against the air pressure; and means for operating the valve in sequence with the operating cycle of the engine.

5. An internal combustion engine, having a cylinder and a piston, and means for admitting air to the cylinder and compressing it by the piston; an atomizing injector, having a passage for air; means for impressing air in the passage, under a higher pressure than the air compressed by the piston; 25 a valve seat in the passage; a liquid fuel passage extending through the valve seat and having an outlet in the valve seat; means for impressing liquid fuel under pressure in the fuel passage, such pressure being greater than the pressure of the air compressed by the piston; 30 a valve engaging with the valve seat, and closing both air and fuel passages, means for operating the valve in sequence with the operating cycle of the engine.

6. An internal combustion engine having a cylinder and a piston, means for admitting air to the cylinder and compressing it by the

piston, an atomizing injector having a passage for air, means for impressing air in the passage under higher pressure than the air compressed by the piston, a valve seat 50 in the passage, a liquid fuel passage extending through the valve seat and having an outlet in the valve seat, means for impressing liquid fuel under pressure in the fuel passage, such pressure also being greater than the pressure of the air compressed by the piston, a vapor passage connecting the atomizer and cylinder, a vaporizer in the vapor passage, a valve engaging with the valve seat, said valve having a single 55 head which closes both air and fuel passages, means for positively closing the vapor passage, and means for opening the valve in sequence with the operating cycle 60 of the engine.

7. An internal combustion engine having a cylinder and a piston, means for admitting air to the cylinder and compressing it by the piston, an atomizing injector having a passage for air, means for impressing air in the passage under a higher pressure than the air compressed by the piston, a valve seat in the passage, a liquid fuel passage extending through the valve seat and having an outlet in the valve seat, means 70 for impressing liquid fuel under pressure in the fuel passage, such pressure being greater than the pressure of the air compressed by the piston, a valve engaging with the valve seat, said valve having a single head for closing the air and fuel 75 passages, means for positively closing the vapor passage and means for opening the valve in sequence with the operating cycle 80 of the engine.

This specification signed and witnessed this 22nd day of November, 1911.

PHILIP D. JOHNSTON.
